UNITED STATES PATENT OFFICE.

GEORGE H. ISLEY, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

REVERSING APPARATUS FOR HEATING FURNACES.

Application filed February 17, 1919. Serial No. 277,543.

To all whom it may concern:

Be it known that I, GEORGE H. ISLEY, a citizen of the United States, residing at Worcester, in the county of Worcester and 5 Commonwealth of Massachusetts, have invented a new and useful Improvement in a Reversing Apparatus for Heating Furnaces, of which the following, together with the accompanying drawings, is a specification.

The present invention relates to improvements in the apparatus which is used with the regenerative type of furnace for reversing the course through such a furnace of the 10 burning gaseous fuel.

The present invention partakes in part of the principles of operation which characterize the reversing apparatus forming the subject matter of my copending applications 15 Serial No. 207,090 and Serial No. 268,391, filed respectively December 14, 1917, and December 26, 1918. The present invention contemplates various novel and improved features in apparatus of this class, involving 20 changes in the construction, arrangement and mode of operation of the apparatus of said copending applications, and in particular, the present invention contemplates the simplification of such apparatus and the 25 provision of instrumentalities operating to render the same wholly automatic in action. The several improved features are fully set forth in the following description and 30 pointed out in the annexed claims, reference being had to the accompanying drawings, in which—

Fig. 1 is a diagrammatic plan view illustrating the adaptation of my invention to a 35 regenerator furnace of well known type.

Fig. 2 is a detail view, partly in section, and on an enlarged scale, of the reversing mechanism proper.

Fig. 3 is a section on the line 3—3 of Fig. 1.

Fig. 4 is a section on the line 4—4 of Fig. 1, and

Fig. 5 is a wiring diagram illustrating the manner in which the automatic reversal of the furnace is effected by the improved apparatus.

Like reference characters refer to like parts in the different figures.

In my two aforesaid copending applications, there is disclosed the utilization in

various forms of a selectively movable hood 55 structure, adapted to establish communication between different pairs of a series of aligned flue terminals, in the act of reversing the furnace. Associated with certain of the flue terminals are swinging gravity-closed 60 covers, each of which is adapted to be automatically opened by the movement of said hood structure into operative position with respect to its associated flue terminal. 65 Whereas in said prior copending applications 70 the reversal of the furnace is dependent upon the provision of either three independent instrumentalities of the character above noted, or two of such instrumentalities of a compound or double construction, the present invention is predicated upon an arrangement of parts which necessitates only two of such instrumentalities, each of the simplest construction, and each functioning 75 with respect to one end only of the furnace. 80 Each of these devices is operative with respect to three aligned flue terminals, and obviously the necessity for only six flue terminals altogether, in contradistinction to the much greater number required in the previous constructions, has the effect of greatly 85 simplifying and minimizing the flue construction, and in addition permits the disposition of the reversing instrumentalities in close proximity to the regenerators of the furnace. Furthermore, the automatic operation of these instrumentalities, as hereinafter described, makes the reversing function directly responsive to temperature conditions in the regenerator passages, and 90 thereby eliminates the guesswork and 95 hazardous operation which is characteristic of the reversal by human agencies.

As shown in the diagram of Fig. 1, which 100 illustrates the application of my invention to a heating furnace, the furnace 1, of any well known type, is provided at opposite ends with the usual gas regenerator passages 2, 2' and the usual air regenerator passages 3, 3', arranged in the manner common to devices of this class. In the use of the duplicate reversing instrumentalities for such a furnace, three coterminous flues are disposed at each end of the furnace adjacent the respective regenerators, and a single 105 hood structure 4, 4' is operatively disposed in relation to each set of said flue terminals. In each of said sets, as illustrated in Fig. 1,

the gas regenerator passages 2, 2' connect with gas regenerator flues 5, 5', and the air regenerator passages 3, 3' connect with air regenerator flues 6, 6'. Adjacent the gas flue terminals 5, 5' are disposed gas supply terminals 7, 7', which connect with a common gas supply passage 8 that receives its supply from a gas producer, or other source, not shown. A stack flue 9 is provided with branches 10, 10' which lead to the respective air regenerator flues 6, 6', as shown in Fig. 1.

As shown in Fig. 2, the duplicate seal castings 11, 11 are constructed to provide terminals for the several alined flues 5, 6, 7 and 15 5', 6', 7', the rims or flanges 12 of said castings being adapted to maintain a sufficient depth of water around and between all of said flue terminals as will be well understood. On opposite sides, near each end, of each of 20 said castings are provided bearing lugs or projections 13, which furnish pivotal support for bell crank levers 14. These levers 14, which are identical in form and construction, but oppositely disposed with respect 25 to each other, are employed for the support and movement of the hoods or reversing instrumentalities 4, 4', in precisely the same manner as described in my aforesaid copending application Serial No. 268,391. 30 Associated with said bell cranks there is shown a counterbalancing device 15 which differs somewhat from that which forms part of the subject matter of said copending application Serial No. 268,391; this operating 35 mechanism is adapted to function in precisely the same manner as that of said copending application, as hereinafter described. It is sufficient at this point to state that the single hoods 4 and 4' of the present 40 invention are adapted to have imparted thereto a parallel motion in precisely the same manner as described in connection with the compound hood structure of said copending application, as by the use of a motor 16, or in any other well known manner; to this 45 end the two hoods 4, 4' may be connected, for movement in unison, by a link 17.

The hood 4 is operative with respect to the flue terminals 5, 6 and 7, and as will be 50 well understood, is adapted to connect the terminal 5 either to the terminal 6 or to the terminal 7, depending upon the position to which it is moved. When the hood 4 connects the terminals 5 and 7, the hood 4' connects the terminals 5', 6', and vice versa, when the hood 4 connects the terminals 5 and 6, the hood 4' connects the terminals 5' and 7'. Each gas supply flue terminal 7, 7' is equipped with a swinging closure 18, which 55 is the counterpart of the swinging closures shown and described in my aforesaid copending applications; each of said closures has a lug 19 for cooperation with the water seal flange of the associated hood 4 or 4', 60 whereby the movement of a hood into opera-

tive relation to the terminal 7 or 7', as the case may be, effects the lifting of the associated closure; the latter descends by gravity to seal the terminal at the beginning of the movement of the hood to its other extreme position.

In each of the branches 10, 10' of stack flue 9, and preferably in close proximity to the flue terminals 6, 6' with which these branches respectively connect, is provided a valve or gate 20, 20', as shown in Figs. 1 and 2. Such valve or gate is herein shown in the form of a vertically slideable damper, which is adapted in its lowest position to shut off the branch 10 or 10' with which it is associated, 75 but obviously any other form of valve may be used without departing from the spirit of the invention. Each valve 20, 20' is adapted to be operated by the movement of the adjacent hood structure 4 or 4', and to 80 this end a chain 21, or other suitable connecting means, is attached between each valve and the short arm of the bell crank 14 which, at each end of the furnace, is immediately above said valve. As a consequence, 85 with the parts in the positions illustrated by Figs. 1 and 2, the valve 20, due to the depression of the short arm of the lever 14 to which it is connected, is allowed to descend by gravity to close the branch 10; while the valve 20' is held by its chain 21 in elevated position so as to keep the branch 10' open.

In this position of the parts, as illustrated in Figs. 1 and 2, the passage of the products of combustion through the furnace is 100 from left to right; at the left hand end of the furnace, the flue terminal 6 is exposed to allow the passage of air therethrough to the air regenerator passage 3 and the gas from the producer, or other source, leaving 105 the flue terminal 7 is confined by the hood 4 and directed into flue 5 and thence to the gas regenerator passage 2 of the furnace. At the right hand end of the furnace, the flue terminal 7' is closed by the cover 18; the products of combustion from the furnace, leaving through the gas and air regenerator passages 2' and 3' are conveyed by the flues 5' and 6' directly to the branch 10', whose valve 20' is held open; it will be seen 110 that such products as pass through the flue 5' are confined by the hood 4' and directed into the flue 6' which connects with branch 10'.

When it is desired to reverse the course of 115 air and gas through the furnace, the hoods 4 and 4' are simultaneously moved into their extreme left hand positions, with the hood 4 covering the flue terminals 5 and 6 and the hood 4' covering the flue terminals 5' and 7'. The initial movement of hood 4 allows the cover 18 to descend by gravity 120 over the flue terminal 7, sealing the same effectively and preventing any loss of gas through this terminal. The final portion of 125

the movement of hood 4' opens the cover 18 of flue terminal 7', and thus the gas from the producer, or other source, passing out of flue terminal 7' is confined by hood 4' and 5 directed into flue 5', whence it passes to gas regenerator passage 2' at the right hand end of the furnace. The uncovering of flue terminal 6' allows the air to enter the regenerator passage 3' at the right hand end 10 of the furnace and, simultaneously, the closure of valve 20' shuts off communication between flue 6' and stack branch 10'. At the other end of the furnace, the products of combustion, leaving the gas and air regenerator passages 2 and 3 are conveyed by the flues 5 and 6 to the branch 10, which is opened to the flue 6 by the lifting of valve 20; it will be understood that such portion 15 of the gases as pass through the flue 5 are 20 confined by the hood 4 and directed into the flue 6.

In order to control the volume of air which enters the furnace through the flue terminal 6 or 6', as the case may be, each of 25 said flues adjacent the regenerator passages 3 and 3' is provided with a gate or damper 22, 22', here shown of the vertically slideable type, although obviously any other form of valve may be used without departing from 30 the spirit of the invention. Each of these dampers 22, 22' is adapted to be operated by the movement of the associated hood structure 4 or 4', and to this end, as shown in Fig. 3, each damper has a chain 23 or 35 other connecting device, which passes over suitable guide pulleys or sheaves 24, 24 and is attached to a hook or other connection 25 on the adjacent side of the associated hood 4 or 4'. As shown in Fig. 3, a plurality 40 of such connection points 25 are provided, in spaced relation along the side of the hood, in order to give an adjustment to the chains 23, whereby the degrees of elevation of the dampers 22 and 22' may be varied. 45 With the parts in the positions illustrated in Figs. 1, 2 and 3 and the air and gas passing through the furnace from left to right, the hood 4 allows the damper 22 to close part way, and thus throttle the entrance of air 50 through the flue 6. Obviously, by shifting the point of connection 25 on said hood, the degree of this throttling may be varied to suit the conditions under which the furnace operates. At the same time, at the other end 55 of the furnace the position of hood 4' is such as to hold the damper 22' in a raised position, to allow the free exit of burning gases from the regenerator passage 3' into flue 6', and thence to the stack. Obviously, 60 the point of connection 25 on hood 4' may be shifted as desired to lower the damper 22' somewhat in order to insure that a proper portion of the burning gases shall 65 pass through the flue 5', under the hood 4' and thence to the stack, as above described.

When the furnace is reversed, by movement of the hoods 4 and 4' to their other extreme positions, the positions of the dampers 22 and 22' are likewise reversed.

The movement of the hoods 4 and 4' and 70 the associated valves and dampers may be readily accomplished by suitable operating devices, such as motor 16, which may be subject to control by the operator in any suitable manner, such for instance as that 75 shown, described and claimed in my aforesaid copending application Serial No. 268,391. In the present instance, however, the reversing function instead of being under the direct control of human agencies, is, 80 by the provision of the novel instrumentalities about to be described, made wholly automatic, and responsive to predetermined temperature conditions prevailing in the furnace flues. To this end, the motor 16 or 85 other driving device is placed under the control of thermostatic elements which are exposed to the heat of the products of combustion, whereby overheating of the regenerator passages of the furnace is effectually 90 and positively prevented.

In Figs. 4 and 5 is indicated diagrammatically an arrangement of apparatus which is designed to accomplish the above purpose, Fig. 4 showing in section the duplicate construction of the flues 6 and 6', between the terminals of said flues and the gates or dampers 22, 22'. In each of said flues, in the vicinity designated, is disposed a thermostatic element 26 of any well known 95 construction, which is here shown as of a character to expand lengthwise when heated, and to contract lengthwise when cooled. The expansion and contraction of the two thermostatic elements 26, which are exposed 100 either to the hot gases from the furnace or to the cool air entering the furnace, as the case may be, is utilized to inaugurate the operation of the motor 16, for example according to the diagram illustrated in Fig. 5. 105

To this end each thermostatic element carries a contact piece 27 which, upon the expansion of the element, is adapted to connect electrically a pair of contact points 28, 29, in the case of the flue 6, and a pair of contact points 28', 29', in the case of the flue 6'. As shown in Fig. 5, the motor 16 is in an electrical circuit which is adapted 115 to be completed by the expansion of either one of the elements 26; in other words, current is supplied to said motor either through the conductors 30, 31, which include the contacts 28', 29', or the conductors 32, 33, which include the contacts 28, 29. Both of these 120 circuits are subject to the operation of a limit switch 34 of any well known construction, the same being here shown diagrammatically as a conducting segment having a gap 35 therein, and adapted to be rotated by the motor 16. 125

With the reversing instrumentalities in the positions illustrated, to cause the exit of hot exhaust gases through the flue 6', it will be clear that the thermostatic element 26 in said flue will gradually expand, and finally its contact piece 27 will connect the points 28' and 29'. Thereupon, a circuit will be established through the conductors 30, 31, the limit switch 34 and the motor 16, causing said motor to drive the shaft 36 which is operatively connected in any suitable way, as by a connecting rod 37, to the adjacent bell cranks 14 of the reversing apparatus. The motor 16 rotates through a sufficient number of revolutions to carry the reversing apparatus into its extreme left hand position, and this rotation, at the same time, causes a half revolution of limit switch 34, so as to bring the gap 35 opposite the conductors 30, 31, thereby breaking the circuit and stopping the motor. In this reversed position of the apparatus, cold air enters the flue 6' and rapidly causes a contraction of the thermostatic element 26 in said flue. On the other hand, the other thermostatic element 26 in flue 6 begins to heat up and when a predetermined temperature is reached, the contact piece 27 of said element makes a connection between the contact points 28 and 29. This completes the circuit through conductors 32, 33, limit switch 34 and motor 16, so as to cause another operation of said motor to reverse the apparatus, the gap 35 of the limit switch being at this time in the opposite position from that shown in Fig. 5.

It will be seen that the reversal of the furnace is made, by the apparatus above described, wholly automatic, the operation of the reversing instrumentalities being responsive to the temperature of the exhaust gases. In other words, the thermostatic elements can be set or adjusted to cause the reversal of the furnace, in every instance, before the regenerator passages of the furnace become overheated, thus maintaining the entire apparatus in a state of highest efficiency, with the possibility for any damage to the flues and regenerator passages by overheating entirely eliminated. If at any time it be desired to reverse the furnace independently of the automatic means provided therefor by the thermostatic elements, the motor 16 can be operated by depressing a switch or button 39 which completes the circuit through a conductor 40. The latter is connected to the conductors 30 and 32 in such a manner, as shown in Fig. 5, as to short-circuit both of the thermostatic elements 26, and thus, in either position of the reversing apparatus and the limit switch 34, the switch or button 39 is operable, when desired, to bring about movement to the other position.

As herein shown the short arms of each

pair of bell cranks 14, extending in opposite directions, have connected thereto the springs 41, 41, which are joined together by a turnbuckle or other adjusting device 42. In either extreme position of the hoods, the springs 41 are under extreme tension, due to the fact that the ends of the short lever arms are the maximum distance apart. The force of the extended springs is therefore exerted to assist the motor 16 in the movement of the hoods 4 and 4'; in other words, the tendency of the springs is to draw the short arms of the bell cranks together, thus minimizing the force required initially to raise the hood structures at the commencement of their parallel motion. When the hoods are at the middle of this motion, the springs lie horizontal, at the limit of their contraction; from this point on, the descent of the hoods makes the force of gravity available to stretch the springs, and thus to store up energy for the next reversing movement.

I claim:

1. The combination with a regenerative furnace, of reversing apparatus therefor constituted by two hoods, one for each end of the furnace, and each operatively related to an air flue and a gas flue of its associated furnace end, and adapted for movement in unison in the act of reversing said furnace.

2. The combination with the two sets of air and gas passages of a regenerative furnace, of a reversing apparatus for said furnace, consisting of one movable hood operatively associated with each set of air and gas passages, said hoods adapted for movement in unison, in the act of reversing said furnace.

3. The combination with the two sets of air and gas flues of a regenerative furnace, of duplicate reversing mechanisms, one associated with each set of air and gas flues, for changing the direction of the gases through said furnace, each mechanism comprising a single hood operatively related to the terminals of an air flue and a gas flue to control the inflow and outflow of gases therethrough.

4. The combination with a regenerative furnace, having air and gas flues at each end thereof, of a stack flue at each end of the furnace leading from one or the other of said air and gas flues, a reversing device at each end of the furnace operable with respect to the terminals of said air and gas flues, and means operable by the movement of said reversing devices for closing one of said stack flues and opening the other.

5. The combination with a regenerative furnace, having air and gas flues at each end thereof, of a reversing device at each end of the furnace operatively related to the terminals of an air flue and a gas flue, and means operable by the movement of said

reversing devices for procuring the distribution of the outgoing gases between the two flues at either end of the furnace.

6. The combination with a regenerative furnace, of a reversing mechanism therefor, and means responsive to temperature conditions within the furnace flues for actuating said reversing mechanism.

7. The combination with a regenerative furnace, of means operable to change the direction of the products of combustion therethrough, and means for automatically actuating said last mentioned means in response to the temperature of said products of combustion.

8. The combination with a regenerative furnace having a reversing device for changing the direction of the products of combustion through said furnace, of actuating means for said reversing device, and means for controlling the operation of said actuating means by the temperature of said products of combustion.

9. The combination with a regenerative furnace, of means for reversing the flow of gases through the flues of said furnace, said reversing means being controlled by the temperatures within said flues.

10. The combination with the reversing mechanism of a regenerative furnace, of means responsive to the temperature in the flues of said furnace for operating said reversing mechanism.

11. The combination with a regenerative furnace, of a reversing means therefor, and temperature operated devices interposed between said furnace and said reversing means for inaugurating the action of the latter.

12. The combination with a regenerative furnace, of means for reversing the flow of gases through said furnace in response to temperature conditions in the exhaust flues of said furnace.

13. The combination with a regenerative furnace, of a reversing means therefor, a motor for operating said reversing means, and thermostatic means adapted to establish an electrical circuit for operating said motor.

14. The combination with a regenerative furnace, of a reversing means therefor, and thermostatic means for controlling the operation of said reversing means.

15. The combination with the opposite sets of flues of a regenerative furnace, of thermostatic means associated with said flues for procuring the reversal of the furnace gases through said flues.

16. The combination with a regenerative furnace, of reversing apparatus therefor comprising two movable hoods, each operatively related to an air regenerator flue and a gas regenerator flue of said furnace.

17. The combination with a regenerative furnace having air and gas passages at each

end, of reversing apparatus for said furnace comprising two separate hoods, each operatively related to an air passage and a gas passage of the furnace.

18. The combination with the two sets of air and gas flues of a regenerative furnace, of a stack passage leading from one of the flues of each set, and means operable in the act of reversing the furnace to open one of said stack passages and to close the other.

19. The combination with a regenerative furnace, of reversing apparatus therefor, comprising a pair of shiftable hoods, each operatively associated with an air flue and a gas flue, and each serving alternately as an inflow and an outflow passage for its associated flues.

20. The combination with a regenerative furnace, of reversing apparatus therefor, comprising a pair of shiftable hoods, one for each end of the furnace, and each controlling the inflow of fresh gases and the outflow of burned gases in respect of the furnace flues associated therewith.

21. The combination with a regenerative furnace, of reversing apparatus therefor, comprising a pair of shiftable hoods, each operatively associated with air and gas regenerator flues and with a gas supply flue, said hoods being movable in unison to control both inflow and outflow of gases through said flues, in the act of reversing said furnace.

22. In apparatus of the class described, a movable reversing member cooperating with the terminals of a set of flues, a stack passage leading from one of said flues, and means operative by the movement of said reversing member to close said stack passage.

23. In apparatus of the class described, a movable reversing member cooperating with the terminals of a set of flues, a cover for the terminal of one of said flues, adapted to be opened by said member, a stack passage leading from one of the other flues, and means responsive to the movement of said reversing member in opening said cover, for closing said stack passage.

24. In apparatus of the class described, a movable reversing member cooperating with the terminals of a set of flues, a cover for one of said flue terminals, adapted to be opened and closed by the movement of said reversing member, and a stack passage leading from one of the other flues and adapted to be opened and closed by the movement of said reversing member.

25. In apparatus of the class described, a movable reversing member cooperating with the terminals of a set of flues, a cover for one of said flue terminals, adapted to be opened and closed by the movement of said reversing member, and a stack passage leading from one of the other flues, and adapted

to be closed upon the opening of said cover and opened upon the closing of said cover.

26. The combination with a set of flues of a regenerative furnace, of means for procuring, selectively, the inflow or outflow of gases through said flues, in the act of reversing said furnace, a stack passage leading from one of said flues, and means for closing said stack passage upon the inflow

10 of gases through said flues.

27. The combination with coterminous air and gas flues at each end of a regenerative furnace, of means for procuring, selectively, the inflow or outflow of gases through said

15 flues, in the act of reversing said furnace,

and associated means for procuring the distribution of the outgoing gases between said flues.

28. In a regenerative furnace, a reversing device constrained for parallel motion, and 20 an expanded spring acting on the centers of such motion, and adapted, by its tendency to contraction, to assist in the movement of said device.

Dated this twelfth day of February, 1919.

GEORGE H. ISLEY.
